SELF OPENING DIE HEAD

Albert F. Breitenstein, New Haven, Conn., assignor to The Geometric Tool Company, New Haven, Conn., a Corporation

Application October 31, 1931. Serial No. 572,239

2 Claims. (Cl. 10—96)

This invention relates to an improvement in self-opening die-heads of the type having an oscillating chaser-operating member carried by a floating chaser-carrying member which is, in 5 turn, organized with a mounting-member in such manner as to axially reciprocate with respect thereto for effecting the unlocking of the die-head by means of the draft exerted upon the chasers themselves by the work.

10 Self-opening die-heads of the type referred to, as heretofore constructed, have been open to the serious objection that the tension of the opening spring of the die-head has tended to cramp the floating chaser-carrying member when the die-head is in its locked position, thus not only causing stiffness of operation, but also causing the chaser-carrying member to assume a highly-objectionable eccentric position with respect to the mounting-member, which becomes more and 20 more marked as wear takes place as an incident to continued use.

The main object of my present invention is to organize and arrange the parts of a self-opening die-head of the type referred to in such manner that the floating chaser-carrying member is not cramped nor thrown into an eccentric position with respect to the mounting-member of the die-head.

With the above and other objects in view as will 30 appear from the following, my invention consists in a self-opening die-head having certain features, and combined and arranged in a novel manner, as will be hereinafter described and particularly recited in the claims.

35 In the accompanying drawings:

Fig. 1 is a view in side elevation of one form which a self-opening die-head embodying my invention may assume;

Fig. 2 is a front end view thereof;

40 Fig. 3 is a rear end view thereof, with a portion of the cover-plate broken away;

Fig. 4 is a longitudinal sectional view taken on the line 4—4 of Fig. 2, but on a larger scale and 45 showing the parts in the positions which they assume when the chasers of the die-head are in their cutting positions;

Fig. 5 is a view corresponding to Fig. 4, but showing the parts in the positions which they 50 assume at the instant of the unlocking of the die-head and prior to the opening thereof;

Fig. 6 is a transverse sectional view taken on the line 6—6 of Fig. 4;

Fig. 7 is a broken transverse sectional view 55 taken on the line 7—7 of Fig. 4;

Fig. 8 is a broken view in longitudinal section taken on the line 8—8 of Fig. 6;

Fig. 9 is a broken view in longitudinal section taken on the line 9—9 of Fig. 6;

Fig. 10 is a broken longitudinal sectional view 60 taken on the line 10—10 of Fig. 6;

Fig. 11 is a broken view in longitudinal section taken on the line 11—11 of Fig. 6;

Fig. 12 is a perspective view of the locking- 65 segment, detached; and

Fig. 13 is a similar view of one of the chasers.

The particular die-head herein chosen for the illustration of my invention includes a mounting-member, generally designated by the numeral 20 and consisting of a rearwardly-extending hollow shank 21 adapted to be mounted in the turret or other appropriate feature of a machine and an annular flange or head-portion 22 located at the forward end of the said shank and provided with a relatively-thin forwardly-extending dirt-excluding lip 23. The said mounting-member is provided with an axial bore, generally designated by the numeral 24 and comprising a relatively-large forward portion 25, mainly located within the head-portion 22, and a relatively-smaller rear portion 26 mainly located within the shank 21.

Mounted within the bore 24 of the mounting-member 20, with capacity for reciprocating movement therein, is the hollow shank 27 of a chaser-carrying member 28 having at its forward end a head-portion 29 corresponding substantially in diameter to the diameter of the head-portion 22 of the said mounting-member 20.

The chaser-carrying member 28 is formed in 90 its forward end with four (more or less) corresponding radial grooves 30 intersecting the outer periphery of its head-portion 29 and the forward end of its axial bore 31. The said grooves also extend from front to rear through the said head-portion 29 and intersect an annular groove 32 formed in the back face thereof. Installed in each of the grooves 30 is a radially-movable chaser 33, each of which is maintained in place in its complementary groove against movement 100 longitudinally of the die-head structure by a key 34.

Each chaser, as shown, is formed in its rear face with a slightly-inclined transverse groove 35 adapted to receive a similarly-inclined cam-lug 36 forwardly projecting from an oscillating chaser-operating ring 37 bearing upon a cylindrical surface 38 upon the chaser-carrying member 28, just to the rear of the head-portion 29 thereof and forming the bottom of what constitutes 110

an annular groove in the periphery of the said chaser-carrying member. The forward wall of the groove just referred to is formed by the back face of the head-portion 29 and the rear wall 5 of which is formed by a retaining-plate 39 constituting, when assembled, a unitary feature of the chaser-carrying member, but made separate for the purpose of ease of manufacture and assembly. The said retaining-plate 39 is secured 10 to the chaser-carrying member 28 by means of dowel-pins 40 and one or more retaining-screws 41 (Fig. 9).

The rear face of the chaser-operating ring 37 is formed with an annular rearwardly-opening 15 groove 42, which houses a locking-segment 43 which latter is provided with a pin 44 forwardly projecting into a clearance passage 45 in the said ring 37 and engaged on opposite sides by opposed tangential clamping-screws 46—46 mounted in 20 the ring 37 with their slotted ends exposed upon the periphery thereof and serving to adjust the position of the locking-segment 43 with respect to the chaser-operating ring 37 for the purpose of determining the size of the thread cut by the 25 chasers 33 as will hereinafter appear.

The rear face of the locking-segment 43, adjacent one of its ends, is cut away to form a locking-abutment or shoulder 47 adapted to be engaged by the head 48 of a reciprocating latching-plunger 49 reciprocating in a bushing 50 mounted in the retaining-plate 39 forming, as before stated, a unitary feature of the chaser-carrying member 28. A helical spring 51 encircles the shank of the latching-plunger 49 and bears at 30 its forward end against the rear face of the head 48 thereof and at its rear end against the bottom of the bushing 50. The rear end of the said bushing, as shown in Figs. 4 and 5, is adapted to reciprocate in a bore 52 in the head-portion 35 40 of the mounting-member 20. The rear end of the bore 52, just referred to, is enlarged to accommodate a nut 53 or collar screw-threaded upon the projecting rear end of the latching-plunger 49 and serving to limit the forward movement thereof under the urge of the spring 51 and to also serve to retract the head 48 from engagement with the locking-segment 43 for unlatching the die-head in the manner to be hereinafter described. Secured by means of screws 50 55 to the rear face of the head-portion 22 of the mounting-member 20, is a washer-like cover-plate 55 having a clearance-recess 55^a, into which the rear end of the plunger 49 and the nut or collar 53 may move on occasion, as will hereinafter appear.

The oscillating chaser-operating ring 37, before referred to, is urged to turn in a clockwise direction, as viewed from the front of the die-head, by a helical spring 56 housed within the 60 annular groove 42 in the rear face of the said ring and bearing at one end against a pin 57 rearwardly projecting into the said groove from the ring 37 itself, and at its opposite end bearing against a pin 58 forwardly projecting into the said groove 42 from the retaining-plate 39.

When the die-head is latched in its working position with its chasers 33 in their inwardly-projected positions, the spring 56 exerts a constant effort to swing the ring 37 clockwise as viewed from the front of the die-head to retract the said chasers, and hence tends to hold the latching-abutment 47 of the latching-segment 43 against the head 48 of the latching-plunger 49. The said chaser-operating ring 37 has projecting from its periphery a stud or post 59 by

means of which the said ring may be turned counterclockwise to reset the die-head after it has been tripped by the retraction of the latching-plunger 49, as will hereinafter appear.

As before pointed out, the chaser-carrying member 28 is organized with the mounting-member 20 so as to have limited axial movement with respect thereto and is normally held slightly forward of its rearmost position by one or more plungers 60, rearwardly projecting through the retaining-plate 39 and engaging with the forward face of the head-portion 22 of the mounting-member 20 (Fig. 9).

The chaser-carrying member 28, together with the parts carried thereby, is normally restrained from moving forwardly from the position in which it is shown in Fig. 4 to that shown in Fig. 5, by one or more helical springs 61 each of which encircles a screw 62 and is located in a chamber 63 formed partly in the chaser-carrying member 28 and partly in the retaining-plate 39, as clearly shown in Fig. 11 of the drawings. As just pointed out, one or more of the springs 61 may be employed and the complementary screw 62 of each projects rearwardly and is threaded into the head-portion 22 of the mounting-member 20.

The die-head herein chosen for the illustration of my invention is in condition for a screw-threading operation when its parts are in the positions in which they are shown in all of the figures of the drawings save Fig. 5. In this position, the chaser-operating ring 37 has been turned counterclockwise so as to cause its cam-lugs 36 to simultaneously project all four of the chasers 33 inward into the bore 31 in position 105 to cut a thread on a piece of work such as that represented by broken lines 64 in Figs. 4 and 5.

The die-head is moved axially toward the work or the work toward the die-head, as may be desired, until approximately the 110 desired length of thread has been cut. Now if the axial bodily movement of the die-head with respect to the work is stopped, but relative rotation between the die-head and the work is continued, the chaser-carrying member, together with the parts organized therewith, will be drawn slowly forward with respect to the mounting-member 20 as the threading operation continues until the latching-abutment 47 of the latching-segment 43 has been moved forwardly, 115 clear of the head 48 of the latching-plunger 49, which latter is held against forward movement at this time by the engagement of the forward face of the nut or collar 53 with an abutment such as the abutment 53^a in the bore 52 and/or the rear end of the bushing 50, as indicated in Fig. 5, which figure shows the parts in the positions which they assume at the instant of such disengagement.

The spring 56 will now be enabled to assert 135 itself to turn the chaser-operating ring 37 in a clockwise direction with the effect of causing the cam-lugs 36 thereof to simultaneously move the chasers 33 outward out of engagement with the work.

The instant that the chasers are freed from the work, as just above described, the chaser-carrying member 28 will be bodily moved rearwardly under the urge of the springs 61 to thus restore the parts to the positions in which they are shown in Fig. 4, save that the latching-plunger 49 will be moved slightly rearwardly by the engagement of the rear face of the latching-segment 43 with the forward end of the said latching-plunger. This 145 rearward displacement of the latching-plunger 150

will be permitted by the clearance-recess 55^a in the plate 55, into which the collar 53 will be free to move.

The die-head may be reset for another threading operation by turning the chaser-operating ring 37 counterclockwise so as to relatch the abutment 47 of the latching-segment 43 with the head 48 of the latching-plunger 49.

Practically all of the major elements of my improved die-head are admittedly old individually, but what I wish to call attention to is the fact that the tension of the spring 56, owing to the novel arrangement of the parts, does not tend to cramp the chaser-carrying member 28 with respect to the mounting-member 20, to thus either prevent necessary freedom of movement or to throw the said chaser-carrying member into a position eccentric with respect to the mounting-member. The objections just referred to are mainly obviated by the fact that the thrust of the spring 56, as the parts are herein organized, can only tend to cramp the retaining-plate 39 with respect to the chaser-carrying member 28, which, of course, cannot take place owing to the fact that they are, to all intents and purposes, a unit.

As before pointed out, the retaining-plate 39 constitutes a unitary feature of the chaser-carrying member 28 and is formed separately therefrom only for convenience in assembling the parts. The chaser-carrying member, therefore, may be viewed, when the retaining-plate 39 is considered a part thereof, as having in its periphery an annular groove in which the chaser-operating ring 37 oscillates.

It will be understood by those skilled in the art that my invention may assume varied physical forms without departing from my inventive concept and I, therefore, do not limit myself to the specific embodiment herein chosen for illustration, but only as indicated in the appended claims.

I claim:

1. In a self-opening die-head, the combination with a mounting-member having a tubular shank provided at its forward end with a flange-like head having a bushing-receiving passage therethrough; of a chaser-carrying unit slidable with respect to the said mounting-member and provided intermediate its front and rear ends with an annular groove, the rear wall of which is formed by a removable plate the rear face of which is normally spaced apart from the front face of the said flange-like head, chasers carried by the said chaser-carrying unit, an oscillating chaser-operating ring installed in the said annular groove and provided at its forward end

with means for operating the said chasers and provided at its rear end with a latching abutment; spring means arranged to turn the said chaser-operating ring in one direction; a bushing having a bottom wall and installed in the said removable plate and projecting rearwardly into the said bushing-receiving passage in the said flange-like head of the mounting-member; a reciprocating latching-plunger having a head and located in the said bushing and projecting rearwardly through the bottom wall of the same, a collar mounted upon the said projecting end of the said plunger and engageable with an abutment carried by the said mounting-member to limit the forward movement of the said plunger; and a spring encircling the shank of the plunger and interposed between the bottom of the chamber in the bushing and the head of the plunger, and closure-means secured to the said mounting-member and closing the bushing-receiving passage therein.

2. In a self-opening die-head, the combination with a mounting-member having a tubular shank provided at its forward end with a flange-like head or annular flange; of a chaser-carrying unit 100 slidable with respect to the said mounting-member and provided intermediate its front and rear ends with an annular groove, the rear wall of which is formed by a removable plate the rear face of which is normally spaced apart from the front face of the said flange-like head, chasers carried by the said chaser-carrying unit, an oscillating chaser-operating ring installed in the said annular groove and provided at its forward end with means for operating the said chasers and 110 provided at its rear end with a latching abutment; spring means arranged to turn the said chaser-operating ring in one direction; a bushing having a bottom wall and installed in the said removable plate and projecting rearwardly into the said bushing-receiving passage in the said flange-like head of the mounting-member; a reciprocating latching-plunger having a head and 120 located in the said bushing and projecting rearwardly through the bottom wall of the same, a collar mounted upon the said projecting end of the said plunger and engageable with an abutment carried by the said mounting-member to limit the forward movement of the said plunger; and a spring encircling the shank of the plunger 125 and interposed between the bottom of the chamber in the bushing and the head of the plunger, and a cover-plate secured to the said flange-like head and recessed to provide clearance for the collar of the said plunger.
